UNITED STATES PATENT OFFICE.

TAGE ELIAS ELIASSON, OF STOCKHOLM, SWEDEN.

MACHINE FOR BOOKKEEPING AND THE LIKE.

Application filed May 3, 1926, Serial No. 106,517, and in Sweden May 18, 1925.

This invention relates to a machine for book-keeping and the like, adapted to be used in combination with a type-writing machine of any known kind.

5 The chief object of the invention is to simplify the booking operation and to simultaneously bring about an effective control.

To this end the invention consists essentially in the combination with a type-writing 10 machine of a drum rotatable with relation thereto and supporting a number of individually and intermittently rotatable rollers for carrying paper strips, means for rotating said rollers, means for holding a band or 15 leaf in place between said type-writing machine and said strips, and means for displacing said band or leaf with relation to said strips.

In the accompanying drawings one form 20 of embodiment of a machine according to the invention is shown. Fig. 1 is a side view of the machine, and Fig. 2 is a top view thereof. Figs. 3 and 4 show details on an enlarged scale. Fig. 5 is a top view of part 25 of the machine on an enlarged scale, certain parts being broken away for the sake of clearness.

In Fig. 1 the dashed and dotted line 1 represents the journal comprising a movable 30 paper band wound about a rotary roller 2 mounted in the frame 24 of the machine. The band 1 is capable of being moved by means of pairs of friction rollers 14 and 15 over the table 3 and the guides 4 to the other 35 side of the machine. The band is lined and provided with columns in the usual way and, besides, divided into segments for later binding.

The one side of the machine, Figs. 2 and 40 5, is adapted for the account-current-book keeping and the other side for the ledger-book keeping, and to this end there is provided at the latter side a rotary drum or cylinder 5 mounted in the frame 24 of the machine and turned by means of a hand wheel 12. The said cylinder 5 is provided along 45 the circumference with equally spaced rollers 6 and curved abutment plates 7, said rollers and plates being disposed in one or more 50 parallel rows, according to Fig. 2 in three parallel rows, each of said rows comprising in the form of embodiment shown 96 rollers 6 and a corresponding number of abutment plates 7, and, consequently, the number of 55 rollers and abutment plates, respectively, of all of the three rows will amount to 288, rep-

resenting a corresponding number of different ledger-book accounts. Wound on another system of rollers 10, Figs. 3 and 4, are paper strips 11, unused ledger-book accounts. 60 Each of said strips 11 runs over the corresponding abutment plate 7, and the free end thereof is secured to the corresponding receiving roller 6. The ledger-book strips 11 and their rollers 6 and 10 are arranged in 65 groups, each of which comprises three accounts. The rollers 6 and 10 of each group are mounted on a plate sector 17, said sectors being applied individually to the drum 5 so as to be capable of being removed independently of each other, thereby facilitating the removal and the insertion of the rollers 10 and the strips 11 and also of the rollers 6, when required, said rollers running on shafts 70 75 25 and 26, respectively secured to said sector plates 17. The abutment plates 7, which run over the whole width of the strips 11, are turnable and actuated by a spring 13 tending to hold the plate in the position indicated at *a* in Fig. 3, i. e. out of engagement with the journal leaf 1, Fig. 1. The roller 6 is provided with a ratchet wheel 18, and cooperating with said wheel are two pawls 19 and 20, the pawl 19, which is integral 80 85 with the abutment plate 7, serving as a driving member for the wheel 18 and the roller 6, and the pawl 20, which is secured to the sector plate 17, serving as an arresting member preventing the wheel 18 and the roller 6 from being turned opposite to the direction 90 of movement caused by the driving member 19. The abutment plate 7 with the pawl 19 is turned against the action of the spring 13 by means of an arm 23 actuated by a lever 95 100 22 turnably mounted in the frame 24 and operated by a push button 21, as clearly shown in Fig. 5.

Located above the delivering roller 2 carrying the journal band or leaf 1 is a type-writing machine 8 capable of being displaced laterally on a guide bar 9 secured to the frame 24, so that the type writing will be performed on the same line across the band 1. Inserted between the said journal band 1 and the paper strips 11 carried by the turnable 105 drum 5 is a carbon leaf 30, Fig. 5. At the other side of the machine, the account-current side, the table 3 forms an abutment for the types of the machine 8. Placed above the journal 1 at this side of the machine are 110 cards or leaves, account-current leaves, and placed between said leaves and the journal 1

are carbon papers, so that the writing on the account-current leaf is copied on the journal.

The book-keeping operation takes place in the following manner:—

5 After the journal 1 has been inserted into the machine and the ledger-strips have also been inserted in the drum 5 between the rollers 6 and 10 and running over the abutment plates 7, the book-keeping is prepared by turning the drum 5, so that the free end of the lever 22 will be located in front of one of the arms 23 and, thus, the types of the type-writer 8 will meet with the corresponding account roller 6, i. e. with the strip 11 carried by said roller and the corresponding abutment plate. Then the abutment plate 7 is turned upwards to the writing position by pushing the button 21 and simultaneously the roller 6 is turned through the action of 15 the pawl 19 and the ratchet wheel 18, causing a winding up of the corresponding ledger-strip 11 on the roller 6 to a degree corresponding to the turning angle, i. e. the tooth pitch of the wheel 18. The ledger-strip 11, the intermediate copying paper and the journal band 1 lie close to each other and are held pressed against the swung up abutment plate 7, and, consequently, the writing on the journal 1 is transcribed on 20 the ledger-strip 11. After the booking has taken place the push button 21 is returned to its initial position and simultaneously also the abutment plate 7 is returned to its initial position by means of the spring 13, the roller 25 6 with the ratchet wheel 18 being prevented from turning backwards by means of the pawl 20. The journal 1 is then moved forwards by turning the friction roller 15. If the writing is to be proceeded on the same account-strip 11, the same button 21 is again pushed down, causing the same abutment plate 7 to be swung up to the working position and causing the said strip 11 to be further wound on the roller 6. If another 30 ledger-account strip 11 belonging to the same row is to be used, the drum 5 is correspondingly turned, and the above-mentioned button 21 is again pushed down. If a ledger-account strip lying for instance in the intermediate row is to be used, the drum 5 is turned so as to present the desired ledger-account strip to the action of the type writer and, then, the intermediate button 21 is pushed down, the number of such buttons 35 corresponding to the number of rows of ledger-account strips. When the ledger strips are to be removed after certain periods, the drum 5 is moved towards the account-current side of the machine, the shaft 16 carrying the drum being to this end elongated, as apparent from Fig. 2.

The invention is not limited to the form of embodiment of the machine shown in the drawing and described with relation thereto, but the details may be constructively varied,

without departing from the spirit of the invention as set forth in the annexed claims.

What I claim is:—

1. In a machine for book-keeping and the like, the combination with a type writing machine of a drum rotatable with relation thereto and supporting a number of individually and intermittently rotatable rollers carrying paper strips, means for rotating said rollers, means for holding a band or leaf located between said type writing machine and said strips, and means for displacing said band or leaf with relation to said strips. 70

2. In a machine for book-keeping and the like, the combination with a type writing machine of a drum rotatable with relation thereto and supporting a number of individually and intermittently rotatable rollers carrying paper strips, means for rotating said rollers, means for holding a band or leaf in place between said type writing machine and said strips, and means for displacing said band or leaf with relation to said strips, said rollers being arranged 85 around the circumference of said drum in at least one row. 90

3. In a machine for book-keeping and the like, the combination with a type writing machine of a drum rotatable with relation thereto and supporting two groups of independently rotatable rollers, the rollers of the one group serving as delivering members and the rollers of the other group serving as receiving members for account strips, means for intermittently rotating said rollers, means for holding a band or leaf in place between said type writing machine and said strips, and means for displacing said band or leaf with relation to said strips. 100 105

4. In a machine for book-keeping and the like, the combination with a type-writing machine of a drum rotatable with relation thereto and supporting a number of individually and intermittently rotatable rollers carrying paper strips, means for rotating said rollers, means for holding a band or leaf in place between said type writing machine and said strips, means for moving said strips individually to a writing position, and means for displacing said band or leaf with relation to said strips. 110 115

5. In a machine for book-keeping and the like, the combination with a type-writing machine of a drum rotatable with relation thereto and supporting two groups of independently rotatable rollers, the rollers of the one group serving as delivering members and the rollers of the other group serving as receiving members for account strips, means for intermittently rotating said rollers, means for moving said strips individually to a writing position, and means for displacing said band or leaf with relation to said strips. 120 125 130

6. In a machine for book-keeping and the like, the combination with a type-writing machine of a drum rotatable with relation thereto and supporting two groups of independently rotatable rollers, the rollers of the one group serving as delivering members and the rollers of the other group serving as receiving members for account strips, means for intermittently rotating said roll-

ers, the rollers of both of said groups being divided into smaller groups supported by separate members detachably secured to said drum, means for holding a band or leaf in place between said type writing machine and said strips, and means for displacing said band or leaf with relation to said strips.

In testimony whereof I affix my signature.
TAGE ELIAS ELIASSEN.
